UNITED STATES PATENT OFFICE.

CHARLES F. PRESCOTT, OF BROOKLYN, NEW YORK, ASSIGNOR TO FRANKLIN RAILWAY SUPPLY COMPANY, OF WILMINGTON, DELAWARE, A CORPORATION OF DELAWARE.

LOCOMOTIVE DRIFTING DEVICE.

1,330,392.

Specification of Letters Patent. Patented Feb. 10, 1920.

Application filed July 30, 1918. Serial No. 247,358.

To all whom it may concern:

Be it known that I, CHARLES F. PRESCOTT, a citizen of the United States, residing at Brooklyn, in the county of Queens and State 5 of New York, have invented a certain new and useful Improvement in Locomotive Drifting Devices, of which improvement the following is a specification.

This invention relates to drifting devices 10 for locomotives, in which a drifting valve is employed for supplying a limited quantity of steam to the engine cylinders when the locomotive is running with the throttle closed.

15 Drifting valves of this character have heretofore been employed and the same have been designed to normally remain closed when the throttle is open and the engine is being operated with live or superheated 20 steam, but are adapted to automatically open to supply a small quantity of saturated steam to said cylinders when the throttle is closed and the locomotive continues running, in order to prevent the formation of 25 a vacuum in the engine cylinders by the pumping action of the pistons, and the consequent drawing of air, gases or cinders into the cylinders.

It is also customary to provide locomotive 30 cylinders with cylinder cocks, one at each end, and manually controlled means for opening said cocks when desired, to drain the cylinder or to blow out the water of condensation. It is important that the 35 drifting steam should not be admitted to the cylinders when the cylinder cocks are open, and that the cylinder cocks should not be opened when the locomotive is drifting, and one of the features of my present 40 improvement comprises broadly, means for supplying steam from the drifting valve to the engine cylinder through the cylinder cock connection, and means for holding the cylinder drain valves closed while the drifting 45 steam is being admitted to the cylinder, thereby preventing the admission of air and the burning of the lubricant. Another feature comprises means for automatically cutting off the supply of steam from the drifting 50 valve when the cylinder cock is opened.

In the accompanying drawing; Figure 1, 55 is a side elevation of a locomotive cylinder having one form of my improved drifting device connected thereto; Fig. 2, an inverted plan of a portion of the engine cylinder

showing the cylinder cock connections, Fig. 3, a vertical longitudinal section of one of the cylinder cocks upon a larger scale; Fig. 4, a transverse section of the cylinder cock taken on the line 4—4 of Fig. 3; and Fig. 60 5, a vertical section of the drifting valve.

My improvement is adapted to be employed in connection with any suitable or preferred form of drifting valve mechanism which operates to supply a limited quantity 65 of steam to the engine cylinders when running with the throttle closed, and closes automatically to cut off said supply when the throttle is opened. One form of drifting valve mechanism is indicated at 7, in 70 the drawing and has a pipe connection 6, leading from the turret and provided with a globe valve 5, in the cab for controlling a supply of saturated steam, a pipe 15 connected with the main live steam supply pipe 75 16, or directly to the engine valve chest 17, and one or more pipe connections 8, with the engine cylinder 10.

According to my present improvement the pipe or conduit 8, for supplying steam 80 from the drifting valve 7, communicates with the engine cylinder through the cylinder cock connection 9. For the purpose of illustration I have shown the two cylinder cocks, one at each end of the cylinder, 85 and each comprising a casing 20, having a connection 9, with the cylinder, and containing a valve 21, for controlling the discharge of water or condensation through the drain outlet 22, the valve being operated 90 by a piston 23, mounted in chamber 24, connected by a pipe 25, with a steam supply and a manually operated control valve 26, in the engine cab. The pipe 8, also connects with the casing 20, and a valve 27, 95 actuated by the piston 23, controls communication from said pipe or conduit 9, into the engine cylinder. As shown, the valve 27, is mounted on the stem 28, of the valve 21, said stem being fluted at 29, to form a guide 100 for the valves and afford a passage for the steam. The capacity of the passages 29 is restricted so that the pressure of the drifting steam may accumulate upon the outer face of the stem 28, and valve 27, and hold 105 the drain valve 21 closed when the drifting steam is flowing to the cylinder.

The branch pipes 6^a and 25^a lead to the duplicate mechanism at the opposite side of the locomotive.

It will be understood that the drifting valve 7, operates to supply a limited quantity of saturated steam from pipe 6, to the pipe or pipes 8, when the locomotive is running with the throttle closed but that this valve automatically closes by the live steam pressure admitted through pipe 15, when the throttle is opened and the supply of live steam flows through the main pipe 16, to the engine valve chest.

The particular construction of the drifting valve mechanism 7, is shown in Fig. 5, and includes the valve 13, operated by the piston 11, in chamber 19, communicating by pipe 15, with the live steam supply of the valve chest. For convenience a number of taps are shown for connecting a drain pipe 12, the taps not used being closed by plugs. This drain pipe preferably leads to the engine exhaust.

When the throttle is shut off and the locomotive continues running, the reduction in pressure in the pipes 16 and 15, and in the chamber 19, permits the drifting valve to open under pressure of steam acting on the face of valve 13, to supply a small quantity of steam from pipe 6, to pipes 8. This supply of drifting steam then flows through the cylinder cocks and their connections 9, into the bottom of the engine cylinder. At the same time the pressure acting on the face of the valve and stem 28, holds the drain valve 21 closed and prevents the admission of cold air through said valves into the engine cylinder. The steam then quickly fills the entire cylinder and valve chamber and moistens and lubricates the walls and valve faces.

As soon as the locomotive comes to a standstill it is the usual practice for the engineer to open the cylinder cocks for draining the cylinders. With the form of cylinder cocks shown he would open the hand valve 26, thus supplying steam pressure through pipe 25, to actuate the pistons 23, to open the drain valves 21, and close the valves 27, to shut off the supply of drifting steam. Then when the throttle is again opened for starting the locomotive the drifting valve is closed and the cylinder cocks return to the normal closed position with the communication from pipe 8, open to the cylinder connections 9.

While I have shown a preferred form of cylinder cock which is operated by fluid pressure, it will be understood that my improvement is not limited to this construction but may also be used with cylinder cocks of any preferred or satisfactory design, whether operated by fluid pressure or otherwise, the important feature being that the operation of opening the cylinder cock also effects the closing of the drifting connection. Other advantages of this combination are that it avoids the necessity of additional

connections into the cylinder and introduces the drifting steam at the most efficient point, that is at the bottom of the cylinder.

Having now described my invention what I claim is:

1. In a locomotive drifting device, the combination of a drifting valve, a cylinder cock controlling an outlet passage from the engine cylinder, a conduit for supplying steam from the drifting valve into the engine cylinder through the said outlet passage from the cylinder to the cylinder cock, and means controlled by the opening of the drifting valve for holding the cylinder cock closed, while the drifting steam is being admitted to the engine cylinder. 70 75

2. In a locomotive drifting device, the combination of a drifting valve, a cylinder cock controlling an outlet passage from the engine cylinder, a conduit for supplying steam from the drifting valve into the engine cylinder, and means controlled by the opening of the drifting valve for holding the cylinder cock closed. 80 85

3. In a locomotive drifting device, the combination of a drifting valve, a cylinder cock controlling an outlet passage from the engine cylinder, a conduit for supplying steam from the drifting valve into the engine cylinder, and means operating automatically to cut off the supply of steam from the drifting valve when the cylinder cock is open. 90 95

4. In a locomotive drifting device, the combination of a drifting valve, a cylinder cock, a conduit for supplying steam from the drifting valve to the engine cylinder, and means actuated by the steam admitted through the drifting valve for holding the drain valve of the cylinder cock closed. 100 105

5. In a locomotive drifting device, the combination of a drifting valve, a cylinder cock, a conduit for supplying steam from the drifting valve to the engine cylinder through the cylinder cock connection to said cylinder, and means actuated by the drifting steam flowing to said cylinder for holding the drain valve of the cylinder cock closed. 110 115

6. In a locomotive drifting device, the combination of a drifting valve, a cylinder cock, a conduit for supplying steam from the drifting valve to the engine cylinder through the cylinder cock connection, and means operating automatically to cut off the supply of steam from the drifting valve when the cylinder cock is open. 120

7. In a locomotive drifting device, the combination of a drifting valve, a cylinder cock, a conduit for supplying steam from the drifting valve to the engine cylinder through the cylinder cock connection, and a single controlled device for simultaneously opening the cylinder cock and closing said conduit. 125 130

8. In a locomotive drifting device, the combination of a drifting valve, a cylinder cock, a conduit for supplying steam from the drifting valve to the engine cylinder through the cylinder cock connection, a valve for said conduit, a piston for opening the cylinder cock and closing said conduit valve, and a hand operated valve for controlling a supply of fluid to said piston.
9. In a locomotive drifting valve device, the combination of a drifting valve, a cylinder cock controlling an outlet passage from the engine cylinder, a conduit for supplying steam from the drifting valve into the engine cylinder through the cylinder 15 cock connection, and a valve in said conduit attached to the drain valve of the cylinder cock.

In testimony whereof I have hereunto set my hand.

CHARLES F. PRESCOTT.
